(57) **CLAIM**

The ornamental design for a bucket lifter applied to bucket, as shown and described.

DESCRIPTION

FIG. 1 is a perspective view of the bucket lifter;
FIG. 2 is another perspective view thereof;
FIG. 3 is a fragmented, enlarged view thereof;
FIG. 4 is a reduced scale, perspective view of the rim of the bucket lifter;
FIG. 5 is a perspective view of the attachment; and,
FIG. 6 is a rear view of the attachment.
The broken lines showing a bucket are for the purposes of illustrating environment and forms no part of the claimed design.
The elements shown in FIGS. 4-6 are shown detached for ease and clarity of illustration.
